H. P. MERRIAM.
DETONATING MECHANISM FOR EXPLOSIVE SHELLS.

No. 431,378.

Patented July 1, 1890.

BY *Paul W. Jordan* ATTY.

UNITED STATES PATENT OFFICE.

HENRY P. MERRIAM, OF NEW YORK, N. Y.

DETONATING MECHANISM FOR EXPLOSIVE SHELLS.

SPECIFICATION forming part of Letters Patent No. 431,378, dated July 1, 1890.

Application filed December 23, 1889. Serial No. 334,695. (No model.)

To all whom it may concern:

Be it known that I, HENRY P. MERRIAM, a citizen of the United States, residing at the city, county, and State of New York, have invented certain new and useful Improvements in Detonating Mechanisms for Explosive Shells, of which the following is a specification.

My invention relates to dynamite or other highly-explosive shells, and its object is to detonate the shell-charge by the blow of immersion on the head of the shell when it strikes a water target, proper provision being made for delay action of the fuses to obtain immersion of the shell under a hostile vessel or other object.

My invention consists of an improved apparatus whereby air is compressed within a chamber contained in the shell by the exterior mechanical action of the water, and such compressed air utilized at a definite time to actuate the detonating mechanism.

My invention also consists of an improved mechanism for locking or retaining the hammers or plungers apart from the fulminate caps under normal conditions and releasing the same automatically at the proper time to be actuated subsequently by pressure.

Referring to the accompanying drawings, Figure 1 is a longitudinal section of the head of the shell; Fig. 2, a front elevation of the apex; Fig. 3, a cross-section on line $x-x$ of Fig. 1; and Figs. 4 and 5, detail side and end views, respectively, of the air-compressing piston.

A is the chamber of the shell filled with high explosive. B is a chamber filled with gun-cotton; C, an annular tube containing fulminating mercury, and D D are time-fuses filled with slow-burning compound—such as meal-powder—to cause delay action, communicating with the tube C and with the primers of the fulminate caps E. These parts, composing the detonator, are contained in a case F, screwed into the apex piece G, which is removable, being screwed into the head of the shell at a.

The case F is provided with cylinders c, which are perpendicular to the axis of the shell, containing hammers or plungers d d', fitting air-tight therein, which, when released, are movable toward the fulminate caps E. It is to be observed that the plungers d d',

are arranged tangentially to circles concentric with the shell intersecting their axes, so that they move severally in different directions. The holes H communicate with the cylinders c at the backs of the plungers and with the space or passage e in front of the case F. The plungers d d', arranged tangentially to a shaft J, are provided with circumferential grooves i at the parts thereof opposite said shaft when the plungers are retracted. The shaft J intersects these grooves i and retains the plungers in their inactive position, but when withdrawn forwardly releases them.

The apex-piece G contains the air-compressing mechanism, which consists as follows: A piston M is fitted to a cylinder N, being made practically air-tight by packings g r, the compressing end of the cylinder opening to the space e and thence to the backs of the plungers d d'. The piston M is provided with a strong spring O, in which motive power is stored to effect the air-compression after the piston is retracted.

K is a spirally-bladed wheel exposed to the action of atmosphere and water at the apex of the shell.

L is a stationary guard placed over the wheel for the purpose of protecting it, and the guard L has inlets l and outlets m, giving free passage-way through the face of the wheel.

The axial shaft J, to which the wheel K is screw-threaded, serves the double function of, first, unlocking the plungers, and, second, retracting the piston against the spring O. To this purpose the shaft J is provided with a pin s, which engages with a slotted collar t, terminal to a sleeve u of the piston M. The slots v v, Fig. 5, in the collar t are located at an angle to the normal position of the pin s, as indicated, so that when the shaft J is moved forward the pin s will abut on the collar and draw the piston M, together with the shaft J, until the former is rotated, so as to bring the slots opposite the pin and trip the piston from the shaft, permitting it to be driven back by the spring. This is accomplished by means of the angular slot w in the surface of the piston, the end w' of which slot is normally in a line opposite the pin w² in the cylinder. After the slot w has passed the pin w² a supplemental longitudinal slot w³, intersecting

the angular slot w , permits the free passage of the piston M over the pin w^2 when tripped.

In the operation of my invention the first part of the movement of the shaft J is imparted by the friction of the atmospheric air on the wheel K , rotating it on the screw-thread of the shaft, and the second part, by the force of the water after immersion, similarly acting on the wheel, and in each case drawing the shaft J forward. The air-actuated rotation of the wheel H , which occurs during the flight of the shell, releases the plungers and draws the shaft J forward until the pin s abuts in the collar t . At the instant of the blow of immersion the wheel K receives continued rotation, drawing the piston against the spring O until the tripping action, hereinbefore described, takes place, compressing the air within the cylinder N and discharging the fulminate caps.

It is to be observed that the time element of delay action may be regulated in the practice of my invention not only by the time composition in the passages D , but also by means of adjustment of the tripping action of the air-compressing mechanism, if desired.

Having thus fully described my invention, what I claim, and desire to secure by Letters Patent, is—

30 1. In an explosive shell, the combination of a detonator actuated by pressure, a cylinder and piston within the shell, a frictionally-actuated wheel on the exterior of the shell, and mechanism whereby the motion of the wheel is imparted to the piston for the purposes described.

2. In an explosive shell, the combination of a detonator actuated by pressure, a cylinder and piston within the shell, a spring operative 40 upon the piston to compress the air, a frictionally-actuated wheel in the exterior of the shell, and mechanism whereby the motion of the wheel is imparted to compress the spring.

3. In an explosive shell, the combination of 45 a detonator actuated by pressure, a cylinder and piston within the shell, a spring operative upon the piston to compress the air, a frictionally-actuated wheel on the exterior of the shell, mechanism whereby the motion of the 50 wheel is imparted to compress the spring, and

a tripping mechanism whereby the spring is released to act on the piston at a given time during the motion of the wheel.

4. The combination, with an explosive shell, of a pressure-actuated detonating plunger or 55 plungers, a shaft intercepting the plungers, and a frictionally-actuated wheel on the exterior of the shell giving longitudinal motion to the shaft to release the plungers.

5. The combination, with an explosive shell, 60 of a detonating plunger or plungers movable in a line perpendicular to the axis of the shell, an air chamber or passage communicating with the backs of the plungers, and a spring-actuated piston for compressing the air in 65 said chamber.

6. The combination, in an explosive shell, of a detonating plunger or plungers perpendicular to the axis of the shell, an air chamber or passage communicating with the backs of the 70 plungers, a spring-actuated piston for compressing the air in said chamber, a screw-threaded axial locking-shaft normally intercepting the plungers, and a spirally-bladed nut on the shaft exposed at the apex of the 75 shell, operative as described.

7. The combination, in an explosive shell, of an air-compressing cylinder and a spring-actuated piston therein, an axial shaft normally intercepting the path of the plungers 80 extending through the piston and the apex of the shell, a spirally-bladed wheel screw-threaded to the shaft, and a tripping device, substantially as described, whereby the piston is engaged by or released from the shaft 85 at definite points of the latter's retraction.

8. As a structural combination, in an explosive shell, a detonator-case containing firing-plungers tangentially arranged about a common axial locking-shaft, a spirally-bladed 90 nut on the shaft exposed at the apex of the shell, and a cylinder-case and an air-compressing piston upon said shaft, longitudinally movable therewith, the whole being combined in a removable apex-piece, substantially 95 as shown.

HENRY P. MERRIAM.
